TUBULAR ELECTRICAL GROUNDING ROD

Harold C. Daniels, Woodbury, Conn., assignor to
 Chase Brass & Copper Co. Incorporated, Wa-
 terbury, Conn., a corporation of Connecticut

Application June 29, 1937, Serial No. 150,988

5 Claims. (Cl. 17—7)

This invention relates to an improvement in grounding-rods for electrical installations, and more particularly to grounding-rods which are of tubular form and adapted to be inserted into the soil to a considerable depth.

One of the objects of the present invention is to provide a superior tubular electrical grounding-rod combining maximum surface area and electro-conductivity with minimum weight.

10 A further object is to provide a superior driving-plunger and grounding-rod combination whereby tubular grounding-rods of relatively-soft high electro-conductive material may be effectively inserted into hard ground without ruinous bending or distortion of such tubular rods.

Another object of the present invention is to provide a tubular grounding-rod structure having means whereby a highly effective electrical connection may be made between the same and a grounding-wire.

With the above and other objects in view, as will appear to those skilled in the art from the present disclosure, this invention includes all features in the said disclosure which are novel 25 over the prior art.

In the accompanying drawings:

Fig. 1 is a perspective view illustrating a mode of installing a tubular electrical grounding-rod of the present invention, adjacent a telegraph pole or the like;

Fig. 2 is a view mainly in vertical central longitudinal section illustrating a tubular grounding-rod as embedded in the earth and showing a driving-plunger therein;

Fig. 3 is a broken view in vertical section showing the tubular grounding-rod as having been driven into the earth to the desired limit, the driving-plunger being removed and the sustaining-plug installed in place and the grounding-clamp attached to the exterior of the projecting end of the tube member of the grounding-rod;

Fig. 4 is a horizontal sectional view taken on the line 4—4 of Fig. 3;

Fig. 5 is a view in side elevation of the driving-plunger;

Fig. 6 is a similar view of the tube member of the grounding-rod;

Fig. 7 is a view in side elevation of the leading-point, detached; and

Fig. 8 is a similar view of the tube-sustaining plug.

The tubular grounding-rod herein chosen for illustration includes in the main a tube member, generally designated by the reference character 55 10, and a leading-point rigidly attached to the

lower portion of the said tube and generally designated by the reference character 11. The tube member 10 is preferably formed of thin-walled copper tubing which may vary greatly with respect to length, diameter and wall-thickness, according to the conditions. For instance, the tube member may vary in length from about two feet to eight or more feet and may vary in external diameter from about one-half inch to about one and one-quarter inch. The wall-thickness of 10 the tube member 10 is preferably within the range of .025" to .035" approximately, to afford maximum surface area for contact with the ground, and at the same time minimize the amount of copper, or the like, which is required. 15

The leading-point 11 may be made of iron and includes a conical head 12 and an axial shank 13 which latter is proportioned to be driven into the lower end of the tube member 10 so as to slightly expand the same and secure a coupling-grip thereupon. The upper surface of the said shank 13 constitutes an anvil-surface 13a and the external diameter of the said shank may, for instance, exceed the internal diameter of the tube member 10 by about .005". At the junction point of the shank 13 with the head 12, the leading-point 11 is formed with an upwardly-facing shoulder 14 against which the lower edge of the tube member 10 rests. Preferably, the largest diameter of the conical head 12 exceeds 25 the external diameter of the tube member 10 by a slight amount sufficient to insure that the said head shall form a complete passage in the soil for the said tube member 10, to thus minimize the friction upon the exterior surface of 30 the said tube member 10 as the same is being driven into the earth in a manner as will hereinafter appear.

In conjunction with the tubular grounding-rod above described, I employ a driving-plunger, 40 which driving-plunger is generally designated by the reference character 15 and includes a relatively-heavy cylindrical hammer-head 16 providing a hand-grip and from which rigidly projects a long rod-like driving-shank 17 freely reciprocatable in the tube member 10 and having a length slightly in excess of the distance from the anvil-surface 13a of the shank 13 of the leading-point 11 to the upper edge of the tube member 10, as is shown in Fig. 2.

After the leading-point 11 has been pressed into the ground by the workman as illustrated in Fig. 1, the driving-plunger 15 is grasped by its hammer-head 16 and is reciprocated up and down in the tube member 10, to thus cause the 50 55

lower end of its shank 17 to hammer against the upper face or anvil-surface 13a of the shank 13 of the leading-point 11. The action just described will drive the leading-point 11 into the 5 soil and since the said leading-point is coupled by a tight frictional fit with the lower end of the tube member 10, said tube member 10 will in effect be drawn downwardly into the soil rather than driven thereinto.

10 After the tubular grounding-rod has been projected into the soil to the desired extent in the manner described, the driving-plunger 15 is withdrawn and a sustaining-plug 18 is installed in the upper end of the said tube member, as 15 illustrated in Figs. 3 and 4. The said sustaining member 18 includes a downwardly-extending cylindrical body 19 and a relatively-narrow head 20 which overlaps the upper edge of the tube member 10. After the sustaining-member 18 20 has been installed in the upper end of the tube member 10, a suitable grounding-clamp such as 21, shown in Figs. 3 and 4, is placed upon the exterior surface of the projecting portion of the tube member 10 and tightened thereupon. The 25 grounding-clamp 21 may be firmly tightened upon the tube member 10 without fear of crushing the same and losing the proper electrical contact therewith, owing to the presence in the interior of the said tube of the cylindrical body 30 19 of the sustaining member 18, which latter member not only serves to prevent collapse of the portion of the tube upon which the grounding-clamp 21 is installed, but the said grounding-clamp also serves to hold the said sustaining 35 member in place in the tube member 10 against withdrawal therefrom. A grounding-wire 22 is connected in any approved manner to the grounding-clamp 21 and is thereafter in thorough electrical connection with the tube member 40 10.

45 By so proportioning the driving-plunger 15 and the tubular grounding-rod so that the lower end of the shank 17 of the driving-plunger impinges upon the anvil-surface of the shank 13 of the leading-head 11 before the under face of the cylindrical hammer-head 16 of the said driving-plunger contacts the upper edge of the tube member 10, it is possible to project thin-walled tubing such as 10 deeply into the soil solely by 50 draft imposed thereon. It will be appreciated in this connection that if an effort were made to drive the thin-walled tube member 10 into the soil by hammering and pounding the upper edge thereof, such tube member 10 would collapse and buckle after but very slight penetration into the soil. As before indicated, the sustaining-member or plug 18 not only serves to sustain the upper portion of the tube member 10 from collapsing under the clamping action of the grounding-clamp 21 but the said grounding-clamp 21 55 serves to compress the adjacent portion of the said tube member against the shank 19 of the sustaining-plug 18 and thus prevents the inadvertent withdrawal of the same from the member 10.

60 By means of the present invention it has been made possible to employ copper or similar relatively-expensive grounding-rod material in place of the heavier and bulkier iron grounding-rods now most generally in use. Not only are such iron grounding-rods of relatively-low conductivity but they are very apt to corrode and disintegrate in the moist soil in which they are usually employed.

65 70 75 If, during the operation of inserting the tubu-

lar grounding-rod into the soil, the frictional grip of the soil upon the tube member 10 should be so severe as to cause the driving-plunger to drive the leading-point 11 slightly out of the tube member 10, the under face of the hammer-head 16 will then come into engagement with the upper edge of the tube member 10 and under these conditions the continued reciprocation of the driving-plunger 15 will act both upon the anvil-surface 13a as well as the upper edge of the tube 10 member 10.

15 The invention may be carried out in other specific ways than those herein set forth without departing from the spirit and essential characteristics of the invention, and the present embodiment are, therefore, to be considered in all respects as illustrative and not restrictive, and all changes coming within the meaning and equivalency range of the appended claims are intended to be embraced therein.

20 I claim:

1. A grounding-device comprising in combination: an elongated tube; a leading-point; and interconnecting-arrangements therefor; the said leading-point being arranged to close the lower 25 end of the tube and having an upwardly extending shank, the said shank terminating in an impact-receiving surface for receiving impact from a driving-element to drive the leading-point axially under all conditions of ground encountered; 30 the said tube and the said shank having such relative diameters as to provide force-fit interconnection thereof; the said force-fit interconnection acting against resistance to impact on the leading-point of the magnitude of ordinary 35 ground-resistance, to cause the said tube to be drawn axially with the driven leading-point to enter ground jointly therewith, and the said force-fit connection being yieldable to force exceeding said ordinary ground-resistance in magnitude, whereby under impact the said leading-point is driven axially forward relatively to the tube and penetration-lag of the tube with respect to the leading-point, is effected.

40 45 50 55 60 65 70 75 80 85 90 95 2. A grounding-device comprising in combination: an elongated tube; a leading-point; and interconnecting-arrangements therefor; the said leading-point being arranged to close the lower end of the tube and having an upwardly extending shank, the said shank terminating in an impact-receiving surface for receiving impact from a driving-element to drive the leading-point axially under all conditions of ground encountered; the said tube and the said shank having such relative diameters as to provide force-fit 50 interconnection thereof; the said force-fit interconnection acting against resistance to impact on the leading-point of the magnitude of ordinary ground-resistance, to cause the said tube to be drawn axially with the driven leading-point to enter ground jointly therewith, and the said force-fit connection being yieldable to force exceeding said ordinary ground-resistance in magnitude, whereby under impact the said leading-point is driven axially forward relatively to the tube and penetration-lag of the tube with respect to the leading-point, is effected; the said tube being arranged to also receive impact-force when retarded, and the said force-fit interconnection being yieldable to permit movement of the tube with respect to its leading-point to counteract penetration-lag of the tube.

3. A grounding-device comprising in combination: an elongated tube; a leading-point; and interconnecting-arrangements therefor; the said 75

5 tube being open at least initially at its upper end for reciprocation of a driving-element therein; the said leading-point being arranged to close the lower end of the tube and having a shank extending upwardly therein, the said shank terminating in an impact-receiving surface for receiving impact from a driving-element to drive the leading-point axially under all conditions of ground encountered; the inside diameter of the 10 tube being less than the outside diameter of the said shank, and the said shank being forcibly inserted in the said tube to provide force-fit interconnection thereof; the said force-fit interconnection acting against resistance to impact on the 15 leading-point of the magnitude of ordinary ground-resistance, to cause the said tube to be drawn axially with the driven leading-point to enter ground jointly therewith, and the said force-fit connection being yieldable to force exceeding said ordinary ground-resistance in magnitude, whereby under impact the said leading-point is driven axially forward relatively to the tube and penetration-lag of the tube with respect to the leading-point, is effected; means for limiting the penetration-lag of the said tube; the said tube being arranged to also receive impact-force when retarded, and the said force-fit 10 interconnection being yieldable to permit movement of the tube with respect to its leading-point to counteract penetration-lag of the tube; and means comprising the abutment-shoulder of the leading-point for limiting the counteracting 15 movement of the said tube.

20 4. A grounding-device comprising in combination: an elongated tube; a leading-point; and interconnecting-arrangements therefor; the said tube being open at least initially at its upper end for reciprocation of a driving-element therein; the said leading-point being arranged to close the lower end of the tube and having an abutment-shoulder and also having a shank extending upwardly therein, the said shank terminating in 25 an impact-receiving surface for receiving impact from a driving-element to drive the leading-point axially under all conditions of ground encountered; the inside diameter of the tube being less than the outside diameter of the said shank, and the said shank being forcibly inserted in the said tube to provide force-fit interconnection thereof; the said force-fit interconnection acting against resistance to impact on the leading-point of the magnitude of ordinary ground-resistance, to cause the said tube 30 to be drawn axially with the driven leading-point, whereby the leading-point and tube jointly enter the ground, and the said force-fit connection being yieldable to force exceeding ordinary ground-resistance whereby the leading-point is driven axially forward relatively to the tube and penetration-lag of the tube is effected to expose the impact-surface of the tube to impact of the upper impact-surface of the driving-element.

35 leading-point to enter ground jointly therewith, and the said force-fit connection being yieldable to force exceeding said ordinary ground-resistance in magnitude, whereby under impact the said leading-point is driven axially forward relatively to the tube and penetration-lag of the tube with respect to the leading-point, is effected; means for limiting the penetration-lag of the said tube; the said tube being arranged to also receive impact-force when retarded, and the said force-fit 10 interconnection being yieldable to permit movement of the tube with respect to its leading-point to counteract penetration-lag of the tube; and means comprising the abutment-shoulder of the leading-point for limiting the counteracting 15 movement of the said tube.

40 5. A grounding-device including in combination: an elongated tube provided with an impact-receiving surface; a leading-point having a shank terminating in an impact-receiving surface; a force-fit connection between the said shank and the said tube; and a reciprocatable driving-element provided with an impact-surface at its lower end and at its upper end, the distance between the lower and upper impact-surfaces of the driving-element being shorter than the length of the said tube and longer than the distance normally between the respective impact-surfaces of the leading-point and the tube, whereby impact is normally delivered only to the impact-surface of the leading-point; the said force-fit connection acting against resistance to impact on the leading-point of the magnitude of ordinary ground-resistance, to cause the said tube to be drawn axially with the driven leading-point, 30 whereby the leading-point and tube jointly enter the ground, and the said force-fit connection being yieldable to force exceeding ordinary ground-resistance whereby the leading-point is driven axially forward relatively to the tube and penetration-lag of the tube is effected to expose the impact-surface of the tube to impact of the upper impact-surface of the driving-element.
